CABLE TOOL DRILL

Charles E. Wilcox, Compton, Calif., assignor to
 Byron Jackson Co., Vernon, Calif., a corpora-
 tion of Delaware

Application September 3, 1937, Serial No. 162,316

5 Claims. (Cl. 255—73)

This invention relates to well drilling bits of the percussion type such as are used in the drilling of oil wells by the cable tool method.

The designs of cable tool drills in general use at the present time are substantially the same as they were 30 or 40 years ago. That is, the drills comprise a shank some 6 to 10 feet in length provided with suitable water courses and one or more chisel blades on the lower end of the shank. Such cable tool bits have several outstanding disadvantages when compared to rotary bits of the type in use today. These disadvantages are: (1) The tendency to deviate from the vertical when drilling in very hard formations, in steeply pitched formations, or formations having alternate hard and soft strata; (2) a very slow cutting speed; and (3) very slow and costly underreaming procedure. It is not uncommon in some fields today for the drill to make only three or four feet of net hole per 24 hour day, due to the three factors enumerated above, even though the drill itself might be capable of digging 20 feet or more in 24 hours in this same formation. The lost time is spent principally in straightening crooked hole and in underreaming the hole already dug. In addition to the disadvantages enumerated above it is often impossible in caving formations, to carry sufficient open hole to permit underreaming while carrying the casing and it is therefore necessary to set one or more extra strings of casing.

It is an object of the present invention to provide a cable tool bit capable of digging straight hole in all types of formations at a speed equal to or greater than present bits.

Another object is to provide a cable tool bit capable of making hole much faster than present bits in average formations.

Another object is to provide an underreaming bit which has no expanding cutters or other detachable parts such as are essential to present types of underreamers.

Another object is to provide a combination bit and underreamer which will underream the hole while digging it, thus permitting the casing to be carried behind the bit when digging in caving formations.

Another object is to provide a combination tool which can be changed from a bit to an underreaming bit by replacing or removing a portion of the cutters.

Another object is to provide a combination tool which can be adapted to various sizes of hole by changing only a part of the bit cutters or underreaming cutters.

Other objects and advantages will appear from the following description of a preferred embodiment of the invention.

Figure 1 of the drawings illustrates a side elevation of one form of the bit in which the entire bit is one solid piece.

Figure 2 is a bottom plan view of the bit shown in Fig. 1.

Figure 3 is a cross section taken on line 3—3 of Fig. 1.

Figure 4 is a cross section taken on line 4—4 of Fig. 1.

Figure 5 is a vertical cross section of a bit similar to that shown in Figs. 1 to 4 but made in two or more pieces so that the upper cutters 18 are replaceable and interchangeable.

Figure 6 illustrates an alternative method of securing the cutters to bits of the type shown in Fig. 5.

Figure 7 illustrates a second alternative method of securing the cutters to bits of the type shown in Figs. 5 and 6.

Figure 8 is a side elevation of one form of underreamer bit in which the entire tool is one solid piece.

Figure 9 is a bottom plan view of the underreamer bit shown in Fig. 8.

Figure 10 is a cross section taken on line 10—10 of Fig. 8.

Figure 11 is a cross section taken on line 11—11 of Fig. 8.

Figure 12 is a vertical cross section of an underreamer bit similar to that shown in Fig. 5 but made in two pieces so that the underreamer cutters are replaceable and interchangeable.

Figure 13 illustrates the drilling bit of Fig. 1 at the upper end of its stroke in a well.

Figure 14 illustrates the underreamer bit of Fig. 8 at the upper end of its stroke in a well.

Figure 15 illustrates an alternative form of 40 drilling bit having detachable and interchangeable reaming cutters.

Figure 16 illustrates a form of underreamer cutter for use with the bit shown in Fig. 15.

The bits illustrated in Figs. 1 to 7, 13 and 15 inclusive are for digging in open hole and comprise a long pilot A, having a cutting face Q at its lower end, a reaming cutter B at the upper end of the pilot, and the usual wrench square C, collar D and threaded pin E. The bit is 50 threadedly attached to a drilling stem F in the usual manner. The pilot cutter may be of any well known type such as a flat chisel blade ("regular" or "Mother Hubbard" bit), a spiral bit or a star bit such as is shown in the draw- 55

- ings. The four bladed star bit is preferable because it tends to drill straighter hole. The pilot cutter should be long enough so that it does not come out of the pilot hole H while digging. Since the length of the drilling stroke is variable the length of the pilot may be varied but should always be as long or longer than the stroke. A pilot of 8 feet to 15 feet in length has been found suitable for general use. The diameter of the pilot cutter is substantially less than the diameter of the hole to be cut. For example, bits having diameters of from 20 inches to 12 inches may have pilot cutters of say twelve to ten inches in diameter. 10 inch and 8 inch bits may have a pilot seven inches in diameter. Thus it may be said that the length of the pilot cutter is approximately 10 to 20 times the diameter thereof, but is preferably about 15 times the diameter.
- 20 The reaming cutters B may be of any well known type and should be of such a diameter, with respect to the diameter of the pilot cutter and the hole, that the reamer and pilot cutters cut approximately equal areas. The reaming cutters B are positioned some 8 to 15 feet above the cutting face of the pilot A. Water courses P of any well known type may be provided.

The reaming cutters B are preferably formed with a slightly concave under surface, that is, they slope upwardly and inwardly toward the vertical axis of the bit. This protects the inner edge G of the shoulder of the pilot hole H (Fig. 13) from crumbling. The cutters B are preferably provided with several short radial cutting teeth O.

It is desirable to keep the pilot cutter A as small in diameter as possible because a small cutter penetrates a hard formation more easily than a large cutter and is less likely to deviate from the vertical. For this reason and the fact that the pilot and reamer cutters should cut approximately equal areas, it is advisable, when making large diameter hole (such as a 20 inch hole) to provide a relatively small diameter pilot and two or more sets of reaming cutters, one above the other, adapted to ream the hole in two substantially equal steps, each step cutting an area approximately equal to the pilot cutter. These reaming cutters may be integral with the cutter body B or may be separate, detachable and interchangeable pieces such as are illustrated in Figs. 5 to 7, and 15 inclusive. Different combinations of pilot and reamer cutters can be used if desired.

Fig. 5 illustrates a pilot A-1 and two sets of reamer cutter subs I and J detachably connected together by means of the usual threaded pin and box construction. The cutters are preferably located above the threaded box portion of the sub so that the threads will not be damaged by heat when the cutters are dressed.

Fig. 6 illustrates a bit in which the pilot A-2 is integral with the upper reamer cutter B-1, the upper end of the pilot being enlarged and threaded as shown at K to receive a threaded sleeve L which forms the lower reamer cutter. The sleeve L is shouldered against the under side of the reamer body as indicated at N to relieve the threads K of the upward thrust of the reamer sleeve L. The upper portion of the pilot adjacent the reamer cutters is preferably made cylindrical and not threaded so that heat will not harm the threads when the reamer cutters are dressed.

Fig. 7 illustrates a modification of Figs. 5 and 6 in which the pilot A-3 is detachable and the lower reamer cutter L-1 is a sleeve as in Fig. 6 but instead of being threadedly connected to the shank it is held in place between the upper shoulder of the pilot A-3 and the lower shoulder of the upper reamer cutter B-2.

The construction described provides a bit which will dig rapidly because the pilot is of relative small diameter and penetrates the formation easily, while the reaming cutters have only to break down the upper edge and corner of the pilot hole, which is easier to do than to drill a full diameter hole of the same size. Moreover, the long pilot and stabilizing reamer cutters keep the bit on the vertical so that the operator can give the bit more weight than would otherwise be the case, thus speeding up the drilling rate even more without danger of making crooked hole.

The bit tends to stay on the vertical because the reamer cutters are dressed out to the full hole diameter and are located a substantial distance (10 to 20 diameters) above the cutting face of the pilot. This construction also eliminates tight hole because the cutting edges of the bit and reamer are dressed out a substantial distance from the shank of the bit.

The operation of the bit is similar to that of any conventional cable tool bit.

Figs. 8 to 11 illustrate a bit similar in most respects to the bit shown in Fig. 1 but adapted to underream at the same time that it makes new hole. The pilot cutter A-4 is similar to the pilot A of the bit shown in Fig. 1. The underreamer cutter R is somewhat like the reamer cutter B but is located on only one side of the pilot A-4, that is, the underreamer cutter is eccentric with respect to the vertical axis of the pilot cutter and the pin collar D-2. As shown in Fig. 9, the radius V of the underreamer cutter is preferably less than the radius W of the hole to be cut but greater than the radius X of the pilot cutter. Thus, when the pilot is reciprocated in the pilot hole while being rotated in the usual manner, the underreamer cutter R cuts a circular hole, the center of which is the vertical axis of the pilot A-4. As illustrated in Fig. 14, the well casing S is carried in the hole some 15 or 20 feet above the bottom of the hole and is lowered from time to time as the bit makes progress. A drill stem F-2 is secured to the upper end of the underreamer bit and extends upwardly into the casing S a short distance. Inasmuch as the underreamer cutter R is eccentric with respect to the well it does not serve as a guide to the same extent as does the reamer cutter B of Fig. 1. Therefore, it is preferable to provide an eccentric stabilizing guide cutter M a short distance below the eccentric cutter R and on the opposite side of the bit body from the cutter R. The cutter M cuts on the same (or a slightly larger) diameter as the pilot cutters and because the cutter is, in use, always dressed out to approximately its full gauge, it serves as a stabilizer at the top of the pilot hole tending to keep the bit on its vertical axis. It is sometimes desirable to provide a guide or stabilizer T on the upper end of the stem F-2 to keep the upper end of the bit centralized in the well. The guide T may be of any of the well known shapes and sizes such as are commonly used for this purpose. While drilling, the guide T should not drop below the lower end of the casing.

The underreamer cutter R may be provided

with exterior fluid channels P—1 as shown in Fig. 1 or it may be provided with one or more longitudinal holes U. The advantage of the holes U is that they permit all of the periphery of the cutter to be utilized for cutting.

Figure 12 illustrates a modification of the underreamer bit of Fig. 8 in which the underreamer cutter R—1 is detachable and interchangeable with respect to the pilot cutter A—5. In the present instance the members R—1 and A—5 are shown as being connected together by means of a threaded pin and box connection, although other constructions could be used. In the preferred embodiment the underreamer body 15 is provided at its lower end with a stabilizing cutter M—1 opposite and somewhat below the reamer cutter R—1.

The underreamer bit described above has no expanding parts, can be run through casing like an expanding underreamer, will cut a hole as large or larger than conventional underreamers, has a greater cutting area on the underreamer cutter than conventional underreamers, and because of the long pilot cutter it tends to make straight hole at all times.

With this underreamer bit the casing can be carried close behind the bit with very little open hole. In many instances this will result in the saving of one or more strings of casing.

30 The bit saves a great deal of time where underreaming is required because it underreams as it digs and does this as fast or faster than a conventional type of bit will make open hole which must then be underreamed.

35 The operation of the underreamer bit is similar to that of the reamer pilot bit or any conventional cable tool bit.

Figures 15 and 16 illustrate a combination bit and underreaming bit somewhat like the tool shown in Fig. 6 but adapted to be used either as a bit (having interchangeable cutters L—2 of the threaded sleeve type), see Fig. 15, or as an underreaming bit (Fig. 16) having interchangeable eccentric reamer cutters of the threaded sleeve type L—3. The sleeve L—3 is preferably, though not necessarily, provided with a stabilizing cutter L—4 positioned opposite the reamer cutter L—3 and somewhat below same. The stabilizing cutter L—4 preferably cuts on the same radius as the pilot cutter Q—5 although it may cut on a slightly larger radius if desired. The reamer cutter sleeves L—2 and L—3 are adapted to seat against a shoulder N—2 on the pilot body A—6 to relieve the threads of the shock load. The pilot A—6 unlike the pilot A—2 of Fig. 6 has no integral reaming cutters B—1, otherwise it could not be used interchangeably as a bit or underreamer bit. The advantage of this construction is that a single pilot can be used with a considerable number of different sizes of reamer or under-

reamer cutters, thus permitting a considerable saving in tool investment.

I claim:

1. A cable tool pilot bit comprising a pilot cutter having a diameter substantially smaller than the diameter of the hole to be cut, an underreamer cutter above said pilot cutter and eccentric to the vertical axis thereof and a stabilizer adjacent the upper end of said pilot cutter and below said underreamer cutter, said stabilizer being eccentric to the vertical axis of the bit and located on the diametrically opposite side thereof from the portion of maximum eccentricity of said underreamer cutter and extending outwardly from said pilot cutter a distance substantially less than said underreamer cutter.

2. A cable tool pilot bit as defined in claim 1 in which the underreamer cutter is substantially annular in shape extending around the axis of said bit approximately 180 degrees.

3. A cable tool drilling bit comprising a pilot cutter having a diameter substantially smaller than the diameter of the hole to be cut, the upper portion of said pilot cutter being enlarged and threaded, and an eccentric underreamer cutter comprising a sleeve threaded internally and adapted to be mounted on said pilot cutter, said eccentric underreamer cutter having a cutting surface at only one side thereof, the radius of said cutting surface being less than the radius of the hole to be cut.

4. A cable tool drilling bit comprising a pilot cutter having a diameter substantially smaller than the diameter of the hole to be cut, the upper portion of said pilot cutter being threaded, and an eccentric underreamer mounted on said threaded portion, said underreamer comprising a sleeve threaded internally, an underreamer cutter disposed at one side of said sleeve and having a cutting radius less than the radius of the hole to be cut but being offset laterally of the vertical axis of said pilot cutter a distance such that the outermost edge of said underreamer cutter is at the edge of the hole to be cut, and a stabilizing cutter on said underreamer positioned opposite and below said underreamer cutter, said stabilizer cutter being adapted to cut on approximately the same radius as said pilot cutter.

5. A cable tool drilling bit comprising a pilot cutter having a diameter substantially smaller than the diameter of the hole to be cut, an eccentric reaming cutter positioned above said pilot cutter and offset laterally of the vertical axis of said pilot cutter, and a stabilizing cutter positioned at the upper end of said pilot cutter at the opposite side to said reaming cutter and below said reaming cutter, said stabilizing cutter having an effective cutting radius at least as great as that of said pilot cutter.

CHARLES E. WILCOX. 60
